UNITED STATES PATENT OFFICE

FRED L. MACKENZIE, OF BEVERLY, MASSACHUSETTS, ASSIGNOR TO UNITED SHOE MACHINERY CORPORATION, OF PATERSON, NEW JERSEY, A CORPORATION OF NEW JERSEY

FASTENING-INSERTING MACHINE

Application filed February 28, 1929. Serial No. 343,429.

This invention relates to fastening inserting machines and is illustrated herein as embodied in a counter stapling machine.

In the manufacture of turn shoes having molded counters it has been customary to fasten a sheet of material known as a tuck into the counter with its lower surfaces in contact with the flange of the counter, thus determining the spread of the forward portions of the counter. It has more recently been proposed, as disclosed in application for Letters Patent of the United States, Serial No. 307,408, filed September 21, 1928 in the name of E. B. Libby, to hold the forward ends of the flange of the counter in the desired spaced relation by a staple one leg of which is anchored in one end only of the flange of the counter and the other leg in the other end only of the flange of the counter, the ends of the flange being separated, except perhaps in the smallest sizes, by a gap which is bridged by the bar of the staple.

It is an object of the present invention to provide a fastening inserting machine for inserting in a counter a staple having a relatively long bar, one leg of the staple being anchored to one end only of the flange of the counter and the other leg to the other end only of the flange, thus determining the spread of the forward portion of the counter. In accordance with a feature of the invention, the illustrated machine is provided with means for forming from wire staples having relatively long bars and driving the staples into the forward portion of the flange of a counter, and a work support on which the counter is carried constructed and arranged to position the counter so that one leg of the staple will be anchored in one end portion only of the flange of the counter and the other leg of the staple will be anchored in the other end portion only of the flange.

A feature of the invention, as embodied in the illustrated machine, comprises an improved work support having gage members arranged to grip the forward portions of the counter at opposite sides thereof, thereby positioning the counter transversely, and an end gage arranged to engage the forward extremities of the flange of the counter, there-

by positioning the counter lengthwise relatively to the fastening inserting instrumentalities of the machine. In the illustrated machine the spread of the counter gripping gage members can be varied by the rotation of a hand wheel which is connected to the gage members, the size of the counter for which the gage members are positioned being shown by an indicator having a movable member connected to the hand wheel.

With the above and other objects and features in view the invention will now be described with reference to the accompanying drawings and pointed out in the claims.

In the drawings,

Fig. 1 is a front elevation of the head and work support of a fastening inserting machine embodying the present invention;

Fig. 2 is a side elevation of the work support of the machine of Fig. 1;

Fig. 3 is a plan view of the work support of Fig. 2;

Fig. 4 is a transverse section on the line IV—IV of Fig. 3; and

Fig. 5 is a perspective view of a counter the spread of the forepart of which is determined by a staple inserted by the illustrated machine.

The illustrated machine is of the character disclosed in Letters Patent of the United States No. 1,016,930, granted February 13, 1912 on an application filed in the name of William H. Borden. As this machine is well-known to the trade and as many of the details of the machine are of no consequence so far as the present invention is concerned, it has not been found necessary to describe the machine in full, only such parts being shown and described herein as are necessary or helpful to an understanding of the present invention. For a full disclosure of the remaining details of the machine reference may be had to said Letters Patent No. 1,016,930.

The illustrated machine is provided with a head in which is mounted a main cam shaft 10 carrying a lifting cam 12 in operative relation to a lifting block 14 carried by a driver bar 16 mounted for vertical movement in ways carried by the head of the ma-

chine and moved downwardly when the lifting cam 12 moves from under the lifting block 14 by a suitable spring in a well-known fashion. Secured to the lower end of the 5 driver bar 16 is a driver 18 reciprocating through a driver passage 20. As the staples inserted by the machine have relatively long bars, the driver 18 is in the form of a flat plate (Fig. 4) and the driver passage 20, which is formed in a driver guide and throat 10 member 22, is of a similar cross section.

An inside former 24 is mounted for forward and rearward movement into and out of the driver passage and cooperates with a 15 pair of outside formers 26 reciprocated in timed relation to the inside former 24 and the driver 18 by suitable mechanism including a rock arm 28 carried by a shaft 30 rocked by suitable connections from the shaft 20. A pair of feed rolls 32 are operative to feed a wire 34 past a pair of cutters 36 and 38 into position above the inside former 24 and beneath the outside formers 26. After the cutter 36 has moved downwardly to sever 25 a length of wire 40, the outside formers 26 are moved downwardly, wiping the end portions of the wire 40 about the inside former 24 and thus forming a staple having a long bar and short legs, as illustrated at 42 in 30 Fig. 4. The inside former 24 is withdrawn and the driver 18 moved downwardly to drive the staple into the forward portions of the flange 43 of a counter 45 presented thereto in the manner shown in Fig. 4.

35 In order properly to position the counter 45 for the reception of the staple, the machine is provided with a work support which will now be described. Attached to a horn post 44, such as is commonly used in such machines, and mounted for vertical movement therewith, is a bracket 46 carrying a substantially straight horn 48 terminating in an anvil 50 having a clenching surface provided with a pair of clenching cavities 52 spaced apart substantially the width of the driver passage 20 and arranged to clench 40 the legs of a staple inserted by the machine.

The bracket 46 also carries gage mechanism for positioning the counter 45 (Figs. 2, 3 and 4) with the forward end portions of its flange 43 in alignment with the clenching cavities 52 and with the legs of a staple in the driver passage 20. This gage mechanism comprises a pair of fingers 60 extending 45 forwardly of the machine and pivoted at 62 to the bracket 46 for horizontal adjustment. Fingers 60 carry at their ends counter engaging portions or members 64, arranged to be positioned within the forward 55 portions of the counter 45 and engaging the under surface of the flange 43 of the counter and the wings 66 of the counter adjacent to the flange, as best shown in Figs. 2 and 4.

Pivoted at 68 to the fingers 60 are a second pair of fingers 70, urged in a counter-

clockwise direction, as viewed in Fig. 2, by a pair of leaf springs 72 anchored at 74 to the fingers 60 adjacent to the pivots 68 and bearing against the lower surfaces of the fingers 70 at their right-hand ends. The 70 left-hand ends of the fingers 70 are provided with portions or members 76 formed and arranged to engage the counter 45 in opposed relation to the members 62 of the fingers 60, as best shown in Figs. 2 and 4.

In order to position the members 64 and 76 of the fingers 60 and 70 for the reception of counters of varying sizes means, which will now be described, is provided for adjusting the fingers 60 and 70 about the pivot 62. For this purpose a shaft 80 is provided having suitable bearings in members 82 carried by the bracket 44. Fast upon the shaft 80 is a barrel cam 84 provided with two cam tracks 86 in which are positioned cam followers or rolls 88 carried by the fingers 60. A hand wheel 90 is secured to one end of the shaft 80 by means of which the shaft can be rotated thereby causing the cam 84 to adjust the gage members toward or from each other. Fast upon the other end of the cam shaft 80 is an indicator wheel 92 provided with graduations 94 which move past a stationary pointer 96 as the hand wheel 90 is rotated. Thus the size of counter for which the gage members are adjusted may be readily determined, the entire range of sizes being cared for, as indicated in Figs. 1 and 3, by somewhat less than one complete revolution of the hand wheel 90.

100 The machine is provided with a friction device, best illustrated in Figs. 3 and 4, to maintain the adjustment of the gage members. This includes a stationary friction member 98 secured to the bracket 46 and a friction member 100 in contact with the friction member 98 and urged thereagainst by a resilient spider 102 bearing against the hub 104 of the hand wheel 90 and against a washer 106 contacting with the friction member 100.

105 In order to position the counter lengthwise, an end gage 110 is provided, clamped by a screw 112 to a projection 114 at the upper end of the horn 48. The end gage 110 is of sufficient width to engage both ends of the flange 115 of even the largest counter and is so positioned that the staple will be inserted a quarter or three-eighths of an inch, more or less, from the end of the flange.

110 In using the machine the operator positions a counter with the ends of its flange in engagement with the end gage 110 and with the portion of the counter where the flange merges into its wings between the gage members 62 and 76, as best shown in Figs. 2 and 4, 115 the position of the gage members having previously been adjusted by rotation of the hand wheel 90 to bring the gage members into proper position for the size of counter which is to be operated upon. The forward por-

tions of the flange of the counter are thus positioned in alignment with the driver passage 20 of the machine so that when the machine is operated to insert a staple the legs of the staple will pass through the flange of the counter, one leg of the staple being anchored in one end only of the flange of the counter and the other end of the staple in the other end of the flange of the counter, as shown in Fig. 5, the space between the two portions of the flange being bridged by the bar of the staple except in the case of very small counters the ends of the flange of which may over-lap slightly.

Having thus described my invention what I claim as new and desire to secure by Letters Patent of the United States is:

1. A counter stapling machine having, in combination, means for inserting in a counter a staple having a relatively long bar, and means for presenting a counter to the staple inserting means with the forward portions of the flange of the counter positioned to cause one leg of the staple to be anchored in one only of the forward portions of the flange of the counter and the other leg of the staple to be anchored in the other only of said forward portions.

2. A counter stapling machine having, in combination, means for inserting in a counter a staple having a relatively long bar, said means including a driver and a throat member provided with a driver passage corresponding in cross section to the dimensions of the staples, a work support constructed and arranged to hold a counter with the forward portions of its flange in alignment respectively with the legs of a staple in the driver passage, and means for operating the driver to drive a staple into the counter thereby anchoring one leg of the staple in one only of the forward portions of the flange of the counter and the other leg of the staple in the other only of said forward portions.

3. A counter stapling machine having, in combination, means for inserting in a counter a staple having a relatively long bar, said means including a driver and a throat member provided with a driver passage corresponding in cross section to the dimensions of the staple, counter supporting and positioning means including a member formed and arranged to be received within a counter and supporting and positioning the counter with the forward portions of its flange in alignment respectively with the legs of a staple in the driver passage, and means for operating the driver to drive a staple through the driver passage and into the flange of the counter thereby anchoring one leg of the staple in one end only of the flange of the counter and the other leg of the staple in the other end only of said flange.

4. A counter stapling machine having, in combination, means for forming staples hav-

ing relatively long bars, a throat member provided with a driver passage corresponding in cross section to the dimensions of the staples and arranged to receive the staples and to conduct them to inserting position, a work support constructed and arranged to hold a counter with the forward portions of its flange in alignment respectively with the legs of a staple in the driver passage, and a driver operable to drive a staple into the counter thereby anchoring one leg of the staple in one only of the forward portions of the flange of the counter and the other leg of the staple in the other only of said forward portions.

5. A counter stapling machine having, in combination, means for forming from wire staples having relatively long bars, a throat member provided with a driver passage arranged to guide the staples to fastening inserting position, a work support, means constructed and arranged to position a counter on the support with the forward portions of its flange spaced apart and in alignment respectively with the legs of a staple in the driver passage, and a driver operable to drive a staple into the counter on the support thereby causing the staple to bridge the gap between the ends of the flange of the counter.

6. A counter stapling machine having, in combination, staple forming and inserting instrumentalities, a work support constructed and arranged to support a counter in operative relation thereto with the forward end portions of its flange in position to receive the legs of a staple inserted by the machine, and two pairs of gage members arranged to grip the forward portion of the counter at opposite sides thereof where the flange merges into the wings of the counter.

7. A counter stapling machine having, in combination, means for forming staples having relatively long bars, a throat member provided with a driver passage arranged to guide the staples to fastening inserting position, counter supporting and positioning means having parts constructed and arranged to be received within a counter and other parts constructed and arranged to engage the exterior of the counter thereby positioning the counter with the end portions of its flange in alignment respectively with the legs of a staple in the driver passage, and a driver operable to drive a staple through the driver passage into the flange of the counter thereby anchoring one leg of the staple into one end only of the flange of the counter and the other leg of the staple in the other end only of said flange.

8. A counter stapling machine having, in combination, means for forming staples having relatively long bars, a throat member provided with a driver passage corresponding in cross section to the dimensions of the staples and arranged to receive the staples, means constructed and arranged to be re-

ceived within a counter and supporting and positioning the counter with the end portions of its flange in alignment respectively with the legs of a staple in the driver passage with 5 a gap between the end portions of the flange at opposite sides of the counter, and a driver operable to drive a staple through the driver passage into the flange of the counter on the support thereby causing the staple to bridge 10 the gap between the ends of the flange of the counter.

9. A work support for a fastening inserting machine having, in combination, a clenching anvil in operative relation to the fastening inserting instrumentalities of the machine, an end gage positioned forwardly of the clenching anvil and formed and arranged to engage the ends of the flange of a counter thereby positioning the counter lengthwise, 20 and gage members formed and arranged to engage the counter rearwardly of the clenching anvil thereby controlling the transverse position of the counter.

10. A work support for a fastening inserting machine having, in combination, a clenching anvil in operative relation to the fastening inserting instrumentalities of the machine, an end gage positioned forwardly of the clenching anvil and formed and arranged 25 to engage the ends of the flange of a counter thereby positioning the counter lengthwise, and two pairs of gage members constructed and arranged to grip the counter rearwardly of the clenching anvil thereby controlling the 30 transverse position of the counter.

11. A work support for a fastening inserting machine having, in combination, a clenching anvil, an end gage adjacent thereto arranged to engage the ends of the flange of a counter thereby positioning the counter lengthwise with respect to the clenching anvil, a pair of side gages arranged to position the counter transversely with respect to the clenching anvil, and means for adjusting the 40 side gages to receive a wider or narrower counter.

12. A work support for a fastening inserting machine having, in combination, a clenching anvil in operative relation to the fastening inserting instrumentalities of the machine, and two pairs of gage members arranged to grip the counter at opposite sides 50 thereof where the flange merges into the wings of the counter thereby positioning the counter transversely, one gage member of each pair being rigidly supported and the other gage member of each pair being yieldingly urged toward the corresponding rigidly supported gage member.

13. A work support for a fastening inserting machine having, in combination, a clenching anvil in operative relation to the fastening inserting instrumentalities of the machine, and two pairs of gage members arranged to grip the counter at opposite sides 60

thereof where the flange of the counter merges into the wings of the counter thereby positioning the counter transversely, one gage member of each pair being rigidly supported and the other gage member of each pair being pivoted to and yieldingly urged toward the corresponding rigidly supported gage member. 70

14. In a fastening inserting machine, the combination of counter positioning mechanism comprising a pair of gage members arranged to be received within a counter and manually adjustable to a position depending upon the size of the counter, a second pair of 75 gage members pivoted to the first pair for movement toward and from the flange of the counter received by the first pair, and a pair of leaf springs urging the gage members of the second pair toward the gage members of the first pair. 80

15. A work support for a fastening inserting machine having, in combination, a clenching anvil, an end gage adjacent thereto arranged to position a counter lengthwise with respect to the clenching anvil, a pair of side 90 gages arranged to position the counter transversely with respect to the clenching anvil, and a barrel cam having two cam tracks arranged to cooperate with followers connected to the side gages whereby rotation of the cam through not more than one complete revolution 95 will adjust the side gages to receive counters of the entire range of sizes.

16. Counter positioning means for a fastening inserting machine having, in combination, two pairs of gage members adjustable toward and from each other and formed and arranged to position the forward portions of the flange of a counter transversely, a hand wheel, and connections between the hand wheel and the gage members whereby rotation of the hand wheel adjusts the gage members of the two pairs toward and from each other to position them for the reception of 100 counters of various sizes. 105

17. Counterpositioning means for a fastening inserting machine having, in combination, two gage members adjustable toward and from each other and formed and arranged to position the forward portions of the flange of a counter transversely, a hand wheel, and connections between the hand wheel and the gage members constructed and arranged so that rotation of the hand wheel through less than one complete revolution 110 adjusts the gage members toward and from each other to position them for the reception of counters of the entire range of sizes, and an indicator including a member movable with the hand wheel to indicate the size of the counter for the reception of which the gage members are positioned. 115

18. A work support for a fastening inserting machine having, in combination, a clenching anvil in operative relation to the 120

fastening inserting instrumentalities of the machine, gage members on opposite sides of the anvil adjustable toward and from each other and formed and arranged to position the forward portions of the flange of a counter transversely, a hand wheel, and connections between the hand wheel and the gage members constructed and arranged so that rotation of the hand wheel through not more than one

5 complete revolution adjusts the gage members toward and from each other to position them for the reception of counters of the entire range of sizes.

19. A work support for a fastening inserting machine having, in combination, a clenching anvil in operative relation to the fastening inserting instrumentalities of the machine, gage members on opposite sides of the anvil adjustable toward and from each other and formed and arranged to position the forward portions of the flange of a counter transversely, a hand wheel, connections between the hand wheel and the gage members whereby rotation of the hand wheel through less than one complete revolution adjusts the gage members toward and from each other to position them for the reception of counters of the entire range of sizes, and an indicator including a member movable with the hand wheel to indicate the size of the counter for the reception of which the gage members are positioned.

20. Work supporting and positioning means for a fastening inserting machine comprising two pairs of gage members arranged to grip a counter at opposite sides thereof thereby positioning the counter transversely, one gage member of each pair being rigidly supported and the other gage member of each pair being yieldingly urged toward the corresponding rigidly supported gage member, a hand wheel, connections from the hand wheel to the adjustably supported gage members constructed and arranged to cause rotation of the hand wheel to adjust said gage members toward and from each other in accordance with the size of the counter to be supported and positioned, and an indicator connected with the hand wheel and arranged 50 to indicate the size of counter for which the positioning means are adjusted.

21. In a fastening inserting machine, mechanism for positioning a counter relatively to the fastening inserting instrumentalities of the machine comprising a pair of arms pivoted for transverse adjustment and having at their forward ends members formed and arranged to engage the inside of a counter toward its forward extremity, mechanism for adjusting said arms, a second pair of arms pivoted to the first pair and having at their forward extremities counter engaging members formed and arranged to engage the outside of the counter in opposition 65 to the counter engaging members carried by

the first pair of arms, and a spring urging the counter engaging members of the arms of the second pair toward the counter engaging members of the arms of the first pair.

22. In a fastening inserting machine, mechanism for positioning a counter relatively to the fastening inserting instrumentalities of the machine comprising a clenching anvil, gage mechanism comprising a pair of arms pivoted for transverse movement about a single axis and having at their forward ends members formed and arranged to engage the inside of a counter toward its forward extremity where its wings merge into its flange, cam mechanism for adjusting said arms through equal arcs but in opposite directions, a second pair of arms pivoted to the first pair and having at their forward extremities counter engaging members formed and arranged to engage the outside of the counter in opposition to the counter engaging members carried by the first pair of arms, and springs urging the counter engaging members of the arms of the second pair toward the counter engaging members of the arms of the first pair.

In testimony whereof I have signed my name to this specification.

FRED L. MACKENZIE.
